ROAD ROLLER

Andrew W. Aitken, Springfield, Ohio, assignor
to The Buffalo-Springfield Roller Co., Springfield, Ohio, a corporation of Ohio

Application March 2, 1937, Serial No. 128,661

12 Claims. (Cl. 94—50)

This invention is a novel improvement in road rollers and like vehicles, and the principal object of the invention is to provide such vehicles with an auxiliary roll disposed intermediate the front and rear rolls or wheels of the vehicle, and disposed slightly in advance of the center of gravity of the vehicle, with novel means for raising and lowering the auxiliary roll in a rectilinear path with respect to the road surface, whereby when 5 the intermediate roll is engaged with the road surface substantially the full weight of the vehicle will be exerted downwardly upon the intermediate roll to roll or smooth any irregularities in the road surface.

10 A further object of the invention is to provide such road roller or vehicle with novel guide frames disposed at opposite sides thereof and rigidly fastened to the roller or vehicle frame, said guide frames having rectilinear guide slots 20 therein sloping downwardly and rearwardly, and having blocks slidably mounted therein, said blocks carrying the ends of the fixed shaft on which the intermediate roll is rotatably mounted; fluid cylinders being provided mounted at opposite sides of the frame substantially in axial alignment with the axis of the guide slots, said cylinders having pistons therein carrying piston rods having their outer lower ends pivotally connected to a second shaft fixedly connected by 25 journal castings to the upper ends of the blocks whereby the blocks are caused to be reciprocated in unison in the guide slots; means being provided for adjusting the connection between the journal castings with the blocks whereby the axis 30 of the intermediate roll may be initially adjusted into parallel relation with respect to the axis of the rear drive rolls or wheels; means also being provided at the lower ends of the guide slots for limiting the downward movement of the blocks 35 in the guide slots whereby when the intermediate roll is in lowermost or operative position the lower periphery of the intermediate roll will lie in the plane tangent to the lower peripheries of the front and rear rolls of the vehicle.

40 Other minor objects of the invention will be hereinafter set forth.

I will explain the invention with reference to the accompanying drawings which illustrate one practical embodiment thereof, to enable others 45 familiar with the art to adopt and use the same, and will summarize in the claims the novel features of construction, and novel combinations of parts, for which protection is desired.

In said drawings:

55 Fig. 1 is a side elevation of a conventional road

roller, showing my novel intermediate roll and mounting applied thereto together with the fluid cylinder operating mechanism, the intermediate roll being shown in lowermost or operative position.

Fig. 2 is a reduced top plan view of the road roller frame with engine or motor removed to expose the operating parts of the mounting.

Fig. 3 is an enlarged side elevation of a portion of the frame showing more in detail my novel intermediate roll and the operating means, the roll being shown in raised position in full lines, and being indicated in lowermost or operative position in dotted lines.

Fig. 4 is a top plan view of the parts shown in Fig. 3.

Fig. 5 is a reduced section on the line 5—5, Fig. 3.

Fig. 6 is a section on the line 6—6, Fig. 3.

The road roller shown is of conventional form, 20 having a single front roller A, mounted in a yoke B, swiveled in the trunnion casting C, the yoke being operated by suitable steering mechanism (not shown). A pair of side frames D are connected with the trunnion casting C, the side 25 frames being arched upwardly over the front roller A. The rear ends of the side frames D are supported by rear wheels E disposed at opposite sides of the side frames and a motor F is mounted in the frame. The above parts are purely conventional, and form no part of my present invention.

In order to provide headroom for the intermediate roller, the lower front portions of the side frames D are recessed as at D' to a point 35 substantially under the center of gravity of the vehicle, the side frames being strengthened and reinforced by channel bars G riveted or otherwise secured thereto along the lower edges of the side frames conforming with the contours thereof.

Mounted in journals G' in the channel irons G slightly in advance of the center of gravity of the road roller is a shaft 1 carrying guides 2 disposed at opposite sides of the vehicle, said guides being substantially channel-shaped as shown in Fig. 6 45 and having webs 2a on their upper faces culminating in a split bearing 2b mounted on the ends of shaft 1, said guides having inwardly extending portions 2c at their lower ends adapted to contact with the under sides of the channel irons G to 50 which the extensions 2c are secured, as by rivets 2d as shown, shims 2e if desired being inserted between the extensions 2c and channels G in order to properly align the axes of the channels of the guides when assembling the parts. The guides 2 55

are thus rigidly secured to the frames D, the same being non-rotatably mounted on shaft 1 by having their lower portions 2c fixed to the undersides of the channels G. The channels of the guides open inwardly as shown in Fig. 6, and are open at their upper ends but closed at their lower ends by walls 2f, and the outer faces of the guides 2 have openings 2g at their lower ends for the insertion of depth stops 3 as shown in Fig. 3. 10 When the guides 2 are thus assembled on the frames the axes of the channel portions of the guides at the opposite sides of the frame will be disposed in the same plane, said axes sloping downwardly and rearwardly of the machine as 15 shown.

Slidably mounted within the guides are blocks 4, preferably also channel-shaped but facing in the opposite direction than the guides as shown in Fig. 6, the upper and lower faces of blocks making a sliding fit within the channels 2. At the lower ends of the blocks are bearings 4a (Fig. 5) receiving the ends of the shaft 5a of the intermediate roll 5, the shaft being non-rotatably retained in the bearings by means of pins 5b (Fig. 25) transfixing the bearings 4a and the ends of the shaft 5. The blocks 4 below the bearings 4a are slightly extended to form contact faces 4b for engaging the lower boxed ends 2f of the guides 2 or to engage the depth stops 3 (Fig. 3) inserted 30 through the openings 2g, so that when the blocks 4 are in their lowermost positions in the guides 2 the lower periphery of the intermediate roll 5 will be disposed in the plane tangent to the lower peripheries of the front and rear rolls A and 35 E. The upper ends of the blocks 4 are preferably boxed as shown at 4c (Fig. 5), and bolted to the boxed ends 4c are bearing castings 6 for a non-rotatable shaft 7 extending between the blocks 4 below the frame channels G whereby both blocks 40 4 are caused to move in unison, the shaft 7 being retained in the castings 6 by means of pins 1a transfixing the castings 6 and the ends of the shaft. Thus the blocks 4 and the non-rotatable shafts 5a and 7 form a rigid unit slidable in the 45 guides 2 and carrying the intermediate roll 5. If desired, shims 8 may be inserted between the castings 6 and blocks 4 for the purpose of adjustment hereinafter explained.

In alignment with the axes of the channels 2 is 50 a shaft 9 journaled in the side frames D of the road roller; and mounted on said shaft are fluid cylinders 10 carrying journals 10a at their upper ends for the shaft 9, said cylinders carrying pistons 10b provided with piston rods 10c having bearings 10d on their outer lower ends which engage the shaft 7, collars 7a (Fig. 4) being provided on shaft 7 for retaining the bearings 10d properly spaced between the castings 6 and the collars 7a.

60 By the above arrangement the blocks 4 carrying the intermediate roll 5 may be moved rectilinearly in guides 2 from inoperative position shown in full lines in Fig. 3, to operative position shown in dotted lines by direct thrust of the pistons 10c of the fluid cylinders 10, and when in operative position the depth stops 3 (if necessary) at the lower ends of the guides 2 will position the intermediate roll 5 so that its lower periphery lies in the plane of the tangent to the lower peripheries 65 of the other two rolls A and E; and by proper selection of shims 8 between bearing castings 6 and the blocks 4 the axis of roll 5 may be initially adjusted so that same will be held by blocks 4 in a position parallel with the axle of drive rolls E. 70

75 The intermediate roll 5 when in operative posi-

tion, being disposed in advance of but near the center of gravity of the road roller, will carry the major portion of the weight of the road roller, and will effectively roll or smooth any irregularities in the road surface. The recessed portions 5 D' of the frames D allow ample headroom for receiving the roll 5 when raised into inoperative position shown in full lines, Fig. 3.

The above described construction thus provides an intermediate roll attachment for road rollers 10 in which the intermediate roll 5 is rectilinearly movably mounted in fixed guides 2 secured to the roller frames D and is lowered into operative position by direct thrust of the piston rods 10c.

I claim:

1. In a road vehicle having a wheeled frame; guides fixedly mounted on the frame adjacent the center of the vehicle; a substantially rigid sub-frame slidably mounted in the guides; a rotatable ground roll carried by said sub-frame and adapted to support the greater portion of the weight of the vehicle when the roll is in operative position engaging the ground; and means for shifting the sub-frame to move said roll into and out of operative position.

2. In combination with a road vehicle as set forth in claim 1, means in said guides for limiting the downward movement of the sub-frame to fix the operative position of the roll.

3. In a road vehicle as set forth in claim 1, members mounted on the sub-frame and connected with the said shifting means; and means for varying the positions of the members with respect to the sub-frame for aligning the same in the guides.

4. In a road vehicle as set forth in claim 1, said sub-frame comprising bearing blocks slidable in the guides; a shaft connecting the blocks and having its ends fixedly secured therein for maintaining the blocks in parallel relation; and said ground roll being journaled on said shaft.

5. In a road vehicle as set forth in claim 1, said sub-frame comprising bearing blocks slidable in the guides; a shaft connecting the blocks and having its ends fixedly secured therein; said ground roll being journaled on said shaft; a second shaft connecting the blocks and having its ends fixedly secured therein; and connections between the frame shifting means and said second shaft.

6. In a road vehicle as set forth in claim 1, interconnected members mounted on the sub-frame adjacent the guides; means for varying the positions of the members with respect to the sub-frame; and said shifting means comprising fluid cylinders adjacent the guides; pistons in said cylinders; and piston rods connecting the pistons with the interconnected members.

7. In a road vehicle as set forth in claim 1, said guides being spaced apart; and means for adjusting the guides on the vehicle frame whereby the axes thereof will lie in the same plane.

8. In a road vehicle having a wheeled frame; members fixedly mounted on the frame adjacent the center of the vehicle and having rectilinear guide channels therein sloping downwardly and rearwardly; a substantially rigid sub-frame slidably mounted in said channels; a rotatable ground roll carried by said sub-frame and adapted to support the greater portion of the weight of the vehicle when the roll is in operative position engaging the ground; and means for shifting the sub-frame to move said roll into and out of operative position.

9. In a road vehicle as set forth in claim 8, a transverse shaft mounted in the vehicle frame

upon which the members are mounted; and said members having portions underlying the frame and secured thereto.

10. An attachment for road vehicles comprising
5 a pair of guides adapted to be secured to the vehicle adjacent opposite sides thereof; a substantially rigid frame slidable in said guides; a ground roll rotatably mounted in the frame; and a fluid cylinder adapted to be mounted on the vehicle and having a piston operatively connected with the frame.

11. In an attachment as set forth in claim 10, said frame comprising bearing blocks slidable in

the guides; a shaft connecting the blocks and having its ends fixedly secured therein for maintaining the blocks in parallel relation; and said ground roll being journaled on said shaft.

12. In an attachment as set forth in claim 10, 5 said frame comprising bearing blocks slidable in the guides; a shaft connecting the blocks and having its ends fixedly secured therein; said ground roll being journaled on said shaft; a second shaft connecting the blocks and having its ends fixedly 10 secured therein, and connections between the pistons and said second shaft.

ANDREW W. AITKEN.
